COPPER OXIDE RECTIFIER

Alfred L. Atherton, Verona, Pa., assignor to
 Westinghouse Electric & Manufacturing Company, a Corporation of Pennsylvania

Application December 31, 1927
 Serial No. 243,904

15 Claims. (Cl. 175—366)

My invention relates to rectifiers and particularly to rectifiers comprising metal discs having chemical compounds of the metal formed on their surfaces placed in contact with terminal plates of a different metal.

One object of my invention is to produce rectifiers or other devices likely to be heated, and which comprise a metal and a compound thereof, with a conducting contact material therefor, which shall undergo no gradual change during their life.

A further object of my invention is to produce oxidized copper rectifiers which shall not deteriorate or otherwise change their electrical characteristics during use.

Other objects of my invention will be apparent upon reading the following specification, taken in connection with the appended drawing in which is shown an oxidized copper rectifier provided with contacts in accordance with my invention.

In the present art, rectifiers comprising discs of copper or other metal having formed on one surface a layer of some chemical compound, such as an oxide, are well known. It appears that the junction between the oxidized layer and the mother metal possesses the property of unilateral conductivity. In consequence of this, if an alternating electromotive force of proper magnitude is impressed in series with this junction, a unidirectional current is caused to flow in the circuit. A problem, however, is presented of making contact between the external surface of the oxidized layer and the remaining conductors of the electric circuit.

One solution of this problem has been found through the use of washers of lead or other impenetrable metal which readily conform to the oxidized surface and make fair electrical contact therewith. However, it has been found that, when contacts are made in this manner, the electrical resistivity of the combined unit gradually rises in the course of its operative life. For many purposes, the resistance rise just mentioned is undesirable and the present invention provides a method of making contact which avoids it.

While my invention is not, in any way, dependent upon the correctness of the following theory, it appears probable that the rise in resistance is the result of the oxidation of the impenetrable lead washer under the influence of heat generated within the body of the rectifier unit when in use. It further appears probable that a part, at least, of the oxidation necessary to the foregoing reaction comes from the layer of oxi-

dized metal. In accordance with my invention, I prevent the gradual oxidation of the metallic washer by forming its surface of a material which is chemically inert to oxidation at the operating temperatures of the rectifier.

As specific methods of giving effect to this fundamental idea, I may form the washer of some soft metal, such as nickel, which is chemically inert to oxidation at ordinary temperatures. Alternatively, I may employ a washer of some soft metal not thus chemically inert but having its surface coated by electroplating or otherwise with a thin film of metal inert to oxidation. In a still further modification, I may coat the surface of the metal with a compound of the very element which combines with the rectifier metal to form the active surface compound thereof. For example, in the case of an oxidized copper rectifier, I may use a lead washer, the surface of which has been subjected to a preliminary oxidation.

In the drawing, Figure 1 is a sectional view of a rectifier embodying my invention and Figs. 2 and 3 are sectional views of modified single rectifier elements. In Figure 1 is shown a rectifier comprising three component elements, each of which consists of a metallic base 1, which may be of copper, and which has a layer 2 of some compound formed on one surface. When copper is used, this compound may be the oxide. United States Patent 1,640,335 discloses ways of making such oxidized copper rectifier units. In contact with the oxide layer 2 is a washer 3 consisting of lead, the contacting surface of which has previously been provided with an oxidized layer 4.

Any desired number of component units such as that just described may be combined to form a circuit element possessing unilateral conductivity. If an alternating electromotive force is impressed between the terminal discs 5 and 6, current will be transmitted freely in that direction in which the copper is negative in potential to its oxidized layer and scarcely at all in the reverse direction. Any desired number of the above described discs may be mounted on a through bolt 7 having an insulated covering 8, as indicated.

In another modification shown in Fig. 2, the contacting washer 9 consists entirely of an impenetrable metal which is chemically inert to oxidation below 200° C., for example, gold or nickel.

In a third modification shown in Fig. 3, the contact washers 10 may consist of lead or other soft metal having a coating such as nickel or gold which is chemically inert to oxidation at temperatures below 200° C.

Accordingly, by means of my invention, I pro-

vide an oxidized metal rectifier with contact plates of such character as to undergo no change in electrical characteristics during the operative life of the rectifier.

5 Where in the following claims the expression "common metal" occurs, it is used to designate metals which are readily obtainable and, therefore, inexpensive as distinguished from the "rare metals" such as gold, platinum and the like.

10 While I have here described particular embodiments of my invention, the broad principles thereof are otherwise applicable in ways which will be apparent to those skilled in the art. I desire, therefore, that the terms of the following 15 claims shall be given the broadest interpretation of which they are susceptible in view of the limitations of the prior art.

I claim as my invention:

20 1. In a rectifier of the type comprising a metal and an oxide of said metal thereon, a contact element cooperating with said compound and having a surface of a composition of common metal, said composition being devoid of chemical affinity for said oxide.

25 2. In a rectifier of the type comprising a metal and a compound thereof with another substance formed thereon, a contact element cooperating with said compound and comprising a common metal chemically inert to said compound at all 30 temperatures at which the rectifier operates.

35 3. In a rectifier of the type comprising a metal and a compound thereof with another substance formed thereon, a contact element cooperating with said compound and comprising an impessible common metal chemically inert to said compound at all temperatures at which the rectifier operates.

40 4. In a rectifier of the type comprising a surface of metal having oxygen in combination therewith, a contact element cooperating with said surface and comprising a composition of common metal, said composition having substantially no tendency to combine chemically with said oxygen.

45 5. In a rectifier of the type comprising a metal and a compound thereof with a non-metallic element, a contact element cooperating with said compound and comprising a common metal chemically inert to said element.

50 6. In a rectifier of the type comprising a metal and a compound thereof with a non-metallic element, a contact element cooperating with said compound and comprising an impessible common metal chemically inert to said compound at all temperatures at which the rectifier operates.

7. In a rectifier of the type comprising a metal and an oxide thereof, a contact element cooperating with said oxide and comprising a surface layer of a composition of common metal, said composition having no tendency to reduce said oxide.

8. In a rectifier of the type comprising a metal and an oxide thereof, a contact element cooperating with said oxide and comprising a common metal chemically inert to said oxide at all temperatures at which the rectifier operates.

8. In a rectifier of the type comprising a metal and an oxide thereof, a contact element cooperating with said oxide and comprising an impossibly common metal chemically inert to oxidation at all temperatures at which the rectifier operates.

9. In a rectifier of the type comprising copper and an oxidized layer formed thereon, a contact element cooperating with said layer and comprising a composition of common metal, said composition being devoid of tendency to take up oxygen from said layer.

9. In a rectifier of the type comprising copper and an oxidized layer formed thereon, a contact element cooperating with said layer and comprising a common metal chemically inert to said layer at all temperatures at which the rectifier operates.

10. In a rectifier of the type comprising copper and an oxidized layer formed thereon, a contact element cooperating with said layer and comprising an impossibly common metal chemically inert to said layer at all temperatures at which the rectifier operates.

10. In a rectifier of the type comprising copper and an oxidized layer formed thereon, a contact element cooperating with said layer and comprising a common metal chemically inert to said layer at all temperatures at which the rectifier operates.

11. In combination with a metal and an oxide of said metal thereon and subject to heat, a contact element cooperating with said oxide and having a surface layer of a composition of common metal, said composition having less chemical affinity for said oxide than said metal has.

11. In combination with a metal and a compound thereof with another substance formed thereon and subject to heat, a contact element cooperating with said compound and comprising a common metal chemically inert to said compound at all temperatures to which said substances are subjected.

12. In combination with a metal and a compound thereof with another substance formed thereon and subject to heat, a contact element cooperating with said compound and comprising an impossibly common metal chemically inert to said compound at all temperatures to which said substances are subjected.

ALFRED L. ATHERTON.
